By Benjamin, Roodhouse & Lundy.

ATTYS.

Patented Dec. 12, 1922.

UNITED STATES PATENT OFFICE.

EUGENE JOHN GARRETT, OF BLUE ISLAND, ILLINOIS.

CAN-FILLING APPARATUS.

Application filed October 12, 1919. Serial No. 330,160.

To all whom it may concern:

Be it known that I, EUGENE JOHN GARRETT, a citizen of the United States, residing at Blue Island, in the county of Cook and State of Illinois, have invented new and useful Improvements in Can-Filling Apparatus, of which the following is a specification.

My present invention relates to improvements in canning machinery, and has especial reference to the provision of devices for filling with liquid cans which are either empty or already contain articles of divers sizes necessitating the adding of different amounts of liquid to the successive cans in order to fill the cans to the proper level for receiving the top or closure.

The specific objects of my invention are, first, the provision of simple mechanism for securing the above results; second, the provision of mechanism which will obviate the necessity of raising or lowering the can prior to and especially after the filling operation which conduces to the slopping or spilling of the fluid from the can; and, third, the provision of mechanism which will retain the fluid in the tank of the machine if through inadvertence no can is in position to receive the same.

The sealing mechanism is so designed that it will readily take care of the ordinary variations of heights in containers without special adjustment, but I have also provided exceedingly simple mechanism whereby the machine can be readily adjusted for containers of divers heights, as will be hereafter seen. A further incidental accomplishment of my device is that it is so designed that it will displace sufficient liquid so that when the filling operation is completed the can will be properly filled for the topping or receiving of the closure instead of having to drain off or remove material in order to provide room for receiving the top.

I attain the various objects of my invention by means of the structure illustrated in the accompanying drawings, in which—

Figure 1 is a central vertical section of the mechanism embodying my invention.

Figure 2 is a top plan of the mechanism shown in Figure 1.

Figure 3 is a detail in section of the fluid dispensing structure, drawn to a larger scale.

Similar reference characters are employed to designate similar parts throughout the divers views. My invention is embodied in

a structure comprising a suitable frame consisting of standards 5 and cross-pieces 6. A vertical shaft 7 is mounted centrally of and to rotate in the frame through the instrumentalities of bushings 8, 8, provided, respectively in and centrally of cross-pieces 6, 6. The central shaft may be rotated by bevelled gears 9 and 10, or in any other suitable and convenient manner.

Secured to shaft 7 is a table 11. In order to make this table vertically adjustable the shaft is threaded, at 12, and a split internally threaded collar 13 is provided which engages the threads upon the shaft for supporting table 11, and a split lock nut 14, which also coacts with the threads upon the shaft, screws down upon the top of the table to hold it in adjusted position. The shaft 7 is, preferably, splined or grooved throughout the threaded portion, and a projection 75 extends from the table into this spline-way so that the table will be rotated with the shaft. This table is provided with any suitable projections, not shown, for properly positioning the cans thereon.

At a distance above the table a tank 15 is secured to shaft 7 in any suitable manner to rotate therewith. The tank 15 can be of any desired form, such as circular, octagonal or polygonal. Secured to the periphery of tank 15 at suitable intervals are cylinders 16, (preferably eight in number) and ports or passageways 17 and 18 located, respectively, near the bottom and top of the cylinders are provided for affording communication between the tank and the respective cylinders.

The top port 18 is provided so that if through the operation of the mechanism the level of the liquid in the cylinder rises above that in the tank it may readily flow back into the tank instead of overflowing the cylinder. The cylinders comprise hollow tubes open at their tops and bottoms to facilitate the passage therethrough of the structure to be hereinafter described.

Mounted to reciprocate within the lower portion of cylinder 16 is a piston-like structure 19, open at the top and having a tapped and threaded bore centrally of its bottom. The top of the piston-like structure will always be lower than the upper return port 18, and for the purpose of permitting the flow of the fluid from port 17 to the interior thereof an elongated opening or port 20 is provided which regis-

ters with port 17 throughout the reciprocation of the piston.

A valve cage 21 is exteriorly threaded upon its lower portion and screwed into the tapped bore of the piston, before mentioned. The upper portion of the valve-cage is centrally bored, at 22, to form a guide for the valve stem, hereafter to be described, and the lower portion of the valve cage is provided with the enlarged bore 23 which communicates with the interior of the piston through a port 24. The lower portion of the valve-cage extends below the piston, and screwed thereon is a disk 25 having a downwardly extending flange 26 in which is mounted a suitable sealing gasket 27, preferably of soft rubber. This sealing gasket may be further secured in proper position by a retaining nut 28 screwed upon the lower extended end of the valve cage. The lower edge of valve-cage 21 is, preferably, beveled, at 29, to form a seat for a valve 30 carried upon the lower end of a stem 31, which extends upwardly through bore 22 of the valve cage and above the top of cylinder 16. Near the top of the valve stem by nuts 32 is secured a collar having a laterally extending arm 33. A spring 34 positioned around the valve stem and between the top of the valve cage and the lower nut 32 maintains the valve normally but yieldingly in closed position. The outer end of the lateral arm 33 is provided with a vertically disposed rod 35 which is guided in a hollow embossment 36 extended from the wall of cylinder 16. The rod 35 is provided with laterally extending stubs 37 and 38 which extend through a slot 39 in the side of the hollow embossment 36, and upon the ends of the stubs are provided anti-friction rollers 40. Secured upon suitable brackets 41 extending from the vertical members 5 of the frame is a circular cam track 42 which passes between the anti-friction rollers 40 of the stubs 37 and 38, herefore described, and said rollers engage, respectively, the top and bottom of the circular cam-track. The cam-track secures its action through the instrumentality of vertically inclined portions 43, which, when engaged by rollers 40 will lower and elevate the guide rod 35 and the valve stem 31 assembled therewith, thus opening and closing valve 30.

Between port 20 and the lower edge of the piston is an annular groove 44 in which is mounted suitable packing 45.

The operation of my devices is as follows:—The rotation of shaft 7, together with table 11 and tank 15 carried thereby will serve the reciprocation of piston 19 in the cylinder 16 through the instrumentality of the circular cam track, rod 35 and stubs 37 and 38. When the packing or sealing gasket 27 comes in contact with the top of the container the further descent of piston

19 will be arrested, but the valve stem 31 through the compression of spring 34 continues downwardly, thereby unseating valve 30 and permitting liquid to flow into the container until the latter is filled. Upon the upward reciprocation of valve stem 31 gasket 27 is maintained in contact with the top of container π through the action of spring 34 until valve 30 is seated when the further upward movement of valve stem 31 will elevate the piston thereby unseating gasket 27 from the top of the can and releasing the can.

The size of the projecting portion of collar 28 and valve 30 is so proportioned that when it is withdrawn from the can the can will not be overflowed, but will be sufficiently full to suitably receive the closure without the necessity of removing fluid therefrom.

From the foregoing description, taken in connection with the drawings, it will be observed that I have provided a simple mechanism for filling containers with fluid which may be adjusted for different sizes of containers; which obviates the vertical movement or shaking of the containers after they have received the liquid; which automatically takes care of ordinary differences in heights of containers; which fills the containers just full enough but not too full; and which will not operate to spill and waste the fluid when no container is in position to receive the same.

What I claim as new is:—

1. In a can filling device, a fluid container, a cylinder having communication therewith, a piston reciprocable within said cylinder, a valve mounted in the bottom of said piston, a stem on said valve having a projection thereon, a spring interposed between said piston and the projection on said stem for yieldingly maintaining said valve normally in seated position, and devices for reciprocating said stem whereby said piston is moved to engage a container and the further movement of said device unseats said valve.

2. Fluid dispensing instrumentalities comprising a cylinder, a hollow piston reciprocable in said cylinder, said piston having a port in one end, a valve controlling said port, a stem arising therefrom, yielding means comprising a spring operating between said piston and said stem for maintaining said valve normally closed, and means acting through said stem for reciprocating it with said piston whereby said valve remains closed until the forward movement of said piston is arrested.

3. Fluid dispensing instrumentalities comprising a cylinder, a piston reciprocable within said cylinder; said piston having a port therethrough, a valve controlling said port, a stem having a projection arising from said valve, a spring interposed between said

piston and the projection on said stem, means acting through said stem for reciprocating it with said piston, and sealing means carried by said piston for engaging a 5 container.

4. In a can filling machine, a fluid tank, and devices for controlling the flow of fluid therefrom to the can to be filled comprising a cylinder in communication with said tank, 10 a hollow piston reciprocable in said cylinder having a port in one end, a valve for controlling said port, a stem arising from said valve, a spring operating between said stem and said piston for maintaining said valve 15 in normally closed position, an element carried by said piston adapted to seal the can to be filled, and means co-acting with said stem whereby said piston is moved to seal the can and the further movement of said means 20 open said valve.
5. A can filling machine comprising a fluid tank, a cylinder in communication with said tank, a piston reciprocable in said cylinder and having a discharge port, a can 25 sealing member surrounding said port, a valve seated in said port having a stem ex-

tended outside said cylinder, an actuating rod connected to said valve stem and having laterally projecting members, a cam-track positioned between said lateral members, and means for causing a relative movement between said tank and cam track. 30

6. A can filling machine comprising a rotatable fluid tank, a cylinder in communication with said tank, a piston reciprocable in 35 said cylinder and having a discharge port, a can sealing member surrounding said port, a valve seated in said port having a stem extending outside of said cylinder, an actuating rod connected to said valve stem and having laterally projecting members, a stationary cam track positioned between said lateral members, and means for rotating said tank whereby said cam track is caused to move said lateral members and thereby seal 40 the can to be filled and open said valve. 45

Signed at Chicago, County of Cook, and State of Illinois, this 3d day of October 1919.

EUGENE JOHN GARRETT.
